UNITED STATES PATENT OFFICE.

HARRIS HERMELIN, OF NEW YORK, N. Y.

MACHINE FOR SHARPENING SAFETY-RAZOR BLADES.

1,073,123.

Specification of Letters Patent. Patented Sept. 16, 1913.

Application filed September 6, 1912. Serial No. 718,669.

To all whom it may concern:

Be it known that I, HARRIS HERMELIN, a citizen of the United States, and a resident of New York, borough of Brooklyn, county of Kings, and State of New York, have invented certain new and useful Improvements in Machines for Sharpening Safety-Razor Blades, of which the following is a full, clear, and exact description.

10 This invention relates more particularly to a machine which is adapted for sharpening blades by the users of safety razors.

One of the principal objects of the invention is to provide a simple and efficient machine which is inexpensive to manufacture and in which safety razor blades of various constructions may be properly held and positioned so that the edges may be sharpened, thus overcoming the necessity for sending 20 the blades to the manufacturers or those having special means for sharpening such blades.

Another object of the invention is to provide a device which may be variously supported and held and so constructed that two rollers having means thereon for sharpening a razor blade may be so operated that one or more blades may be simultaneously 25 acted on by both of the rollers, at the same time permitting the rollers to have a fabric as well as a leather surface so that the blades may first be operated on by the fabric and then by the leather to finish and make the edge keen and sharp.

30 Other objects of the invention are to provide simple and efficient means for supporting the machine; to provide simple means whereby the sharpening rollers may be rotated; and to provide simple and efficient 35 means whereby the blades may be relatively adjusted to properly position them with relation to the sharpening rollers.

A further object of the invention is to provide a simple and effective safety blade 40 holder and clamping means which are adapted to permit the blades to be readily removed and inverted so that the blade may be acted on first by one portion of the rollers and then by the other to finish the sharpening thereof.

With these and other objects in view, the invention will be hereinafter more particularly described with reference to the accompanying drawings, which form a part of 55 this specification, and will then be pointed

out in the claims at the end of the description.

In the drawings, Figure 1 is a side elevation of one form of machine embodying my invention. Fig. 2 is a vertical section, taken on the line II—II of Fig. 1. Fig. 3 is a rear elevation. Fig. 4 is a plan view. Fig. 5 is a sectional plan, taken on the line V—V of Fig. 1. Fig. 6 is a side elevation of the blade holder showing how a plurality of 60 blades may be held therein, the said blades being of different makes. Fig. 7 is an elevation showing the blade holder in an open position. Fig. 8 is a sectional plan through the holder, taken on the line VIII—VIII of Fig. 6; and Fig. 9 is a section taken on the line IX—IX of Fig. 6.

The machine has a base 10 to which is fastened a bracket 11. This bracket 11 has two horizontally extending portions 12 and 13, the latter being secured to the base and the former having a threaded opening through which passes a threaded bolt 14. This bolt has a clamping end 15 and a thumb portion 16 forming with the bracket 17 substantially what is known as a C-clamp which is adapted to fit about a table 17 or other support to detachably clamp the machine thereto, though instead of the C-clamp the base may have a sharpened metallic projection to which may be attached a handle in a manner similar to the ordinary screw driver or file in which a pointed shank is forced into the handle.

A bracket 18 has a substantially T-shaped 90 end 19 which is secured to the base 10 and has an upright portion 18^a and an overhanging part 20. This part 20 has apertures in the open end thereof in which the ends of roll shafts 21 and 22 are journaled. The 95 shafts 21 and 22 extend vertically in front of the upright portion of the bracket 18 and have their lower ends journaled in the base 10. A semi-cylindrical roll 23 is held to each of the shafts and one portion, as 100 the upper part thereof, is covered by canvas or like sharpening member 24, and the lower half or portion is covered with a leather sharpening member 25, though the 105 position of these sharpening members or elements may be reversed or other means provided. The roll on the shaft 21 has its straight portion opposed to the curved or convex portion of the roll of the shaft 22 so that as said rolls rotate in unison, only 110

one roll will act upon the blade or blades at the same time for a purpose to be presently described. Each of the roll shafts 21 and 22 is provided with a gear 25^a which 5 gears intermesh, and meshing with one of the gears 25^a, as the gear on the shaft 22, is a larger driving gear 26. This gear is supported on a lug or stud 27 forming a part of the clamping bracket 11, and on said 10 gear 26 is a handle 28 by which the gear 26 may be rotated. It will be evident that as the gear 26 is rotated by the handle 28, the two gears 25^a and the two rolls 23 will be also rotated.

15 To hold the razor blades and to permit adjustment thereof in order that the blades may be sharpened properly by the rolls, various means may be employed. As shown a clamping or holding member 29 is provided. This member may be of steel, brass or any suitable springy metal and has a clamping body portion 30 which is substantially U-shaped in cross-section, as shown best in Figs. 5, 8 and 9. The member 29 20 at the upper end is provided with two substantially L-shaped arms 31 extending on opposite sides thereof and these arms are fastened at their upper ends to pendent parts 32 of a plate-like member 33. This member 25 33 is substantially U-shaped in plan to provide an open part 34 to permit access to the clamping body portion 30 of the member 29, and said member 33 is slotted, as at 35, for the stem of a screw 36 to adapt said member 30 to be rigidly clamped to the part 20 of the bracket 18, and to be adjusted laterally thereof by means of the screw 36 and slot 35. The arms 31 are adapted to be engaged by the threaded ends of screws 37 and these 40 screws have their body portions passed through slots 38 to adapt the arms 31 with their body portion to be adjusted toward or from the rolls 23 and transversely of the adjustment of the plate-like member 33.

45 The body portion 30 of the member 29 at the lower end is provided with an L-shaped foot 39 having a plurality of slots 40 through which extend the screws 41 or other fastening means. The screws 41 have their 50 threaded stems engaging threaded apertures in the plate or member 42. This plate or member is provided with a slot 43 through which pass screws 44. The screws 44 and slot 43 permit adjustment of the plate or 55 member 42 in a direction similar to the adjustment of the plate 33, and the slots 40 and screws 41, as well as the screws 37 and slot 38, permit adjustment of the clamping member 29 toward and from the rollers, 60 so that said clamping member may be adjusted in two directions.

A blade holder 45, Figs. 2 and 5 to 9, is provided. This holder in the form shown comprises two members 46 and 47. These 65 members are hinged together at their upper

edges by the hinge 48 and at their lower edges by the hinge 49 so that the said members may be closed or opened for the insertion and removal of the safety razor blades. The members 46 and 47 are bowed or enlarged, as at 50, so as to fit within the curved part 51 of the clamping member 29 and have straight blade-like parts 52. The parts 52 may be provided with openings 53 in one of the members, as the member 47, and the member 46 may be provided with integral spring tongues 54 opposed to the openings 53 serving to assist in holding and clamping the razor blades. In some blades as manufactured, an opening is provided and to assist in holding blades of this kind in position one of the members of the blade holder, as the member 47, may have a projection or pin 55 which is adapted to pass through the opening of the razor blade into the opening 56 in the member 46 of the blade holder, thus positioning the blade as shown in Figs. 6 and 9. The lower part of the blade holder may have depressed portions 57 and integral tongues or parts 58 which serve 90 as backings for the razor blade, as shown in Figs. 6 and 8. The razor blade 59 shown in these latter figures has a backing which rests against the tongues 58 to position the same, and the blade is engaged by the depressed spring portions 57 serving to hold the same in position.

In practice the blade holder may be made to hold one or two blades as desired, though usually only one, and said blade is arranged at the upper or lower portion according to the character of the blade. That is, the clamping and holding means differs according to the character or make of the blade. The holder, when one or more of the blades 100 are positioned, as shown in Figs. 6 to 9, is inserted lengthwise from above into the body portion 30 of the clamping member 29. The body portion 30 having its sides yielding, will clamp and force the members 46 and 47 of the blade holder together and will sustain the blade in its proper position. The clamping member 29 may be adjusted in two directions as already explained so as to properly position the blades with respect 110 to the rollers 23, and when properly positioned, the said rollers with the sharpening members or material are rotated by means of the gears 25^a and 26. The blade will be first acted on by one roller and then by the 115 material on the other roller, but not both at the same time otherwise it would be difficult to adjust the rollers in such a way as to give a sharp edge to the blade. When the blades have been acted on by the material, as the canvas at the upper part of the roller, the blade holder may be removed by inserting the fingers through the opening 34 of the member 33, and when inverted will place the blade which was uppermost in a position 130

to be acted on by the material carried at the lower part of the rollers, as the leather for example. If the rollers are rotated in the manner described, the leather part on the rollers will finish the sharpening process and give the blades a keen edge, thus the rollers by providing the two surfaces, permit the blades to be sharpened as readily as the ordinary razor blades can be sharpened by the usual form of strop having the leather and canvas.

Having thus described my invention, I claim as new and desire to secure by Letters Patent:—

15 1. In a machine of the character described, the combination of a plurality of rolls, each of said rolls provided with different sharpening material on different parts thereof, means for rotating the rolls, a clamping member having a U-shaped body portion provided with laterally extended arms at the upper portion thereof and a foot at the lower portion thereof and two adjustable plates to which the clamping member is

25 adjustably held.

2. In a machine of the character described, the combination of a plurality of rolls having means for sharpening razor blades, means for rotating the rolls, a clamping member having a substantially U-shaped body portion and provided with laterally extending arms at the upper portion thereof and a foot at the lower portion thereof, a plate having means for adjustment relative to the rolls and with respect to the clamping member, and a second plate to which the clamping member is adjustably held and itself adjustable with relation to the rolls.

3. In a machine of the character described, the combination of a plurality of rolls having means for sharpening razor blades, means for rotating the rolls, a clamping member having a U-shaped body portion and provided with laterally extending arms at the upper portion thereof and a foot at the lower portion thereof, and two adjustable plates to which the clamping member is adjustably held.

4. In a machine of the character described, the combination of a plurality of rolls having means for sharpening razor blades, means for rotating the rolls, a clamping member having a substantially U-shaped body portion, a blade holder, a plate having means for adjustment relative to the rolls and with respect to the clamping member, and a second plate to which the clamping member is adjustably held and itself adjustable with relation to the rolls.

5. In a machine of the character described, the combination of a plurality of rolls having means for sharpening razor blades, means for rotating the rolls, a clamping member having a body portion and provided with laterally extending arms at the upper portion thereof and a foot at the lower portion thereof, a blade holder arranged in said clamping member, and two supporting plates to which said clamping member is adjustably secured.

This specification signed and witnessed this fourth day of September A. D. 1912.

HARRIS HERMELIN.
